UNITED STATES PATENT OFFICE.

CHARLES C. WIENTGE, OF PROVIDENCE, RHODE ISLAND, ASSIGNOR TO
THE HOWARD STERLING COMPANY, OF SAME PLACE.

DESIGN FOR A HANDLE FOR SPOONS, &c.

SPECIFICATION forming part of Design No. 21,838, dated September 6, 1892.

Application filed August 9, 1892. Serial No. 442,619. Term of patent 7 years.

To all whom it may concern:

Be it known that I, CHARLES C. WIENTGE, of the city of Providence, in the county of Providence and State of Rhode Island, have 5 invented and produced a new and original Design for Handles of Spoons and Similar Articles, of which the following is a specification, reference being had to the accompanying drawings, forming part thereof.

10 Figure 1 represents an obverse view of a handle, showing my new design. Fig. 2 represents a reverse view of a handle, illustrating my new design.

The leading features of my new design consist in the wave-like outline forming alternating curved enlargements and slight contractions in the width of the handle and gradually increasing the width of the same toward the upper end ornament, beadings extending 15 along the edges of the handle-neck, an overlapping scroll ornament at the center of the neck, a scroll ornament on the lower end of the neck, a foliated scrolled ornament extending from the upper portion of the neck onto 20 the first enlargement, and a series of foliated scrolls forming borders around the enlargements and joined at the top of the handle by 25 a shell-like ornament extending partially around a scroll, on the reverse of the handle 30 beadings extending along the edges of the neck, a foliated ornament on the upper end thereof, lengthened scrolls slightly foliated forming borders around the enlargements, and a scroll-ornamented shell-like finial forming 35 the upper end of the handle.

3 in the drawings designates the bowl of a spoon. It may, however, represent the tine portion of a fork or a portion of any similar article to which the handle is applicable.

40 4 designates the handle. From the article 3 the outline of the handle extends upward and curves slightly outward to 5 5, where the

same is slightly contracted. The outline then curves boldly outward and upward to 6 6, again slightly contracts, and finally curves 45 outward and inward to meet the ornament 7, forming the upper end of the handle. The obverse surface of the handle is ornamented at the lower end of the handle by the scroll 8, located between the beadings 9 9, which extend along the edges of the handle to 5 5, a 50 scrolled leaf 10, overlapping the central portion of the neck, an enlarged scrolled and foliated ornament 11, extending over the upper portion of the neck and onto the first enlargements to form a portion of the scrolled 55 ornament 12, forming a side border of this enlargement, the scrolled foliated ornament 13, forming the border on the other side of this enlargement, and the foliated scrolls 14 60 14, forming the borders of the second enlargement and joined at their upper ends by the scroll 15, partially surrounded by the shell-like border 16. The reverse of the handle is ornamented by the beadings 17 17, extending 65 along each edge of the neck to 5 5, the foliated scroll 18 on the upper portion of the neck, the background of this portion being roughened, the scrolled ornaments 19 19, forming 70 borders for the first enlargement, the scrolled ornaments 20 20, forming the borders of the second enlargement, and the scroll 21 on the roughened surface of the shell-like ornament 22 at the upper end of the handle.

What I claim is—

The design for handles of spoons and similar articles, as herein shown and described.

In witness whereof I have hereunto set my hand.

CHARLES C. WIENTGE.
